(57) **CLAIM**

The ornamental design for a camera housing with camera, as shown and described.

DESCRIPTION

FIG. 1 is a top, front and right side isometric view of a camera housing with camera.

FIG. 2 is a top, rear and right side isometric view thereof.

FIG. 3 is a bottom, front and left side isometric view thereof.

FIG. 4 is a front elevational view thereof.

FIG. 5 is a rear elevational view thereof.

FIG. 6 is a right side elevational view thereof.

FIG. 7 is a left side elevational view thereof.

FIG. 8 is a bottom plan view thereof; and,

FIG. 9 is a top plan view thereof.

The broken lines depict portions of the camera housing with camera in which the design is embodied that form no part of the claimed design.
